SARATH KUMAR GHOSH, OF SEATTLE, WASHINGTON.

AUTOMATIC TRAIN OR CAR STOPPING APPARATUS.

1,153,616.

Specification of Letters Patent. Patented Sept. 14, 1915.

Application filed June 23, 1914. Serial No. 846,872.

To all whom it may concern:

Be it known that I, SARATH KUMAR GHOSH, a subject of the King of Great Britain, residing at Seattle, in the county of 5 King and State of Washington, have invented certain new and useful Improvements in Automatic Train or Car Stopping Apparatus, of which the following is a specification.

10 My invention relates to an improved method for stopping automatically a train or car that uses an air-brake, on passing a signal set at stop.

My invention is equally applicable where 15 the block system of signaling is used or the manual system of signaling; the setting of the semaphore signal at stop-position by either system sets automatically this apparatus into activity for stopping the train or 20 car. Also, my invention stops the train or car by automatically opening a valve in the air-line by merely mechanical action without the use of any electrical device.

My invention consists of two parts: first, 25 a mechanism connected with the semaphore signal and hereinafter called the track instrument; second, an apparatus on the engine or car. I now describe these in detail, illustrated so far as needed by the accompanying drawing, in which—

Figure 1 gives a side view of the track instrument. Fig. 2 gives a side view of the apparatus in the engine or car which is rendered active by the track instrument, and 35 which opens a valve on the air-line. Fig. 3 gives a vertical section of the valve in the air-line, showing the relative position of the pin at the top which keeps the valve closed, and the coiled spring at the bottom which 40 opens the valve when the pin is removed.

Same numbers refer to same parts in the several views.

The track instrument may be placed on the ground to lie below the passing engine or car, or be suspended from above over the passing engine or car, or be placed laterally so as to stand by the side of the passing engine or car (Fig. 1). I prefer this last method and describe it here.

50 In Fig. 1 a pole (1) of suitable height is

placed by the side of the track. On top of the pole a rod (2) is hinged so as to rotate in a vertical plane at right angle to the rails, any suitable form of hinge being used which prevents the rod (2) from rotating too far 55 back. The rod (2) is connected by a wire or chain (4) to the semaphore signal (5); this connection is made according to the semaphore convention of each particular railway so that, whatever be that convention, the rod (2) is pulled out of the way of 60 passing cars and rendered inactive when the semaphore signal stands at clear-position, but the rod (2) descends or gravitates to a horizontal position and becomes active 65 when the signal is set at stop-position. In this method, if a malicious person cuts the wire or chain (4), or the said wire or chain is destroyed by the act of God, its only effect is to render the track instrument active. 70 Hence such tampering or accident cannot endanger the train, but merely arrest it.

Upon the pole (1) there is a hook or support (6) which limits the descent of the rod (2) to the desired horizontal position; the 75 top of the hook or support (6) may be U-shaped so as to prevent lateral torsion of the rod (2). At the outer extremity of the rod (2) there is a small cross-arm (3); when the track instrument is in the active 80 or horizontal position this cross-arm (3) engages a brush (7) projecting horizontally from the apparatus of the engine. In the engine apparatus (Fig. 2) the said brush (7) is attached to a rod (8) which is pivoted 85 at (9) to some suitable support on the engine, the pivot permitting horizontal movement; the broken line to the right of (9) shows the wall of the engine. The rod (8) further passes through a horizontal slit at 90 the top of the stand (10) so that the rod is not permitted to have any vertical movement, and has only horizontal movement within the slit. The slit contains a lateral spring on each side of the rod so as to maintain the rod in a steady position without 95 undue lateral vibration owing to the motion of the engine, but when the rod has to move under the actuation of the track instrument the spring allows the necessary movement. 100

At its inner extremity the rod (8) terminates as at (11) alongside the pin (14) which is hereinafter described.

The pipe of the engine or car carrying the air for the brake, herein called the air-line, has a prolongation pipe (12) ending in a slide valve (13), the sliding part of which moves up and down in a vertical direction. The valve contains a coiled spring at its lower end (not shown in Fig. 2) which presses upward the sliding part of the valve. At the top of the valve in a vertical position there is a thin metal pin (14) which presses downward on the sliding part of the valve. The downward pressure of the pin counteracts the upward pressure of the coiled spring and keeps the valve closed; but if the pin be removed, the upward pressure of the spring would open the valve and thus open the air-line and arrest the train or car. Thus if the engine passes a signal set at stop, the track instrument actuates the brush (7) on the rod (8), and the consequent horizontal movement of the rod causes its inner extremity (11) to knock out the pin (14) and thereby arrest the train.

Fig. 2 shows a rest or bracket (15, 16) which upholds the engine apparatus at some suitable part of the engine. The bracket sustains a box-like cover indicated by dotted lines, over the apparatus within the body of the engine, so as to keep out dust from its delicate parts and also prevent foolish or malicious tampering.

Fig. 3 shows a view of the valve in a vertical section; (17) is the slide which closes or opens the air-passage, and (20) the coiled spring beneath it, the flange or socket holding (17) in position being provided with ball-bearing or other suitable device for lessening friction, if necessary; (19, 19) is the orifice from the air-line to the external atmosphere; (18) is the corresponding orifice on (17) here viewed in section from the side. Hence if the pin (14) be removed, the slide (17) would be pushed upward by the spring (20), so that the orifice (18) would come in a straight line with (19, 19) and thus open the air-passage, the upward movement of slide (17) being limited to the desired amount by the hook or catch (21). The upper end of the pin (14) is held in position by (22) which is a projection from some fixed part of the valve or of the engine. There may be a very slight indentation on the under part of (22) and the top part of (17) between which the pin is inserted, so as to keep the pin from falling off with the vibration of the engine and so that it will need the lateral thrust of the rod (11) to throw out the pin.

It is desirable that the pin be made of thin metal so that it becomes slightly bent by this ejection and unusable a second time.

Thus if the engineer be supplied with a given number of pins for each run, then each pin he has used up acts as a record against him of having gone past a signal set at stop. This makes for greater care and efficiency.

When the valve is opened in the manner of this invention and the air passes out of the exhaust orifice (19, 19) this escape of air is used to blow a whistle (23). For this purpose a short conduit pipe is placed at the exhaust orifice to take in all or a portion of the escaping air, and the whistle (23) is attached to the conduit pipe. The blowing of the whistle instantly warns the engineer that the brake is being automatically applied. He may instantly shut off steam or propelling power, or carry out any other duty prescribed for the emergency.

I have shown the pin (14) as placed above the valve and the spring (20) as placed below it; but the relative positions of the pin and spring may be reversed. In that case, if the pin be placed below the valve, instead of a spring pressing downward on the valve a weight may be used in preference.

I have mentioned a slide valve as being the type of valve I prefer for this invention; but any other type of valve may be used, provided it is kept closed by a removable pin or similar device, the said pin or similar device being automatically removed when arresting the train.

I have shown the track instrument as being placed on the side of the engine; but if it be placed above or below the engine, then the relative direction of the engine apparatus will also be altered accordingly.

Likewise, although I have shown and described certain preferred forms of my invention by way of illustration, I do not limit myself to the precise details of construction herein described, as modifications and variations may be made within the scope of the claim without departing from the spirit of the invention.

I am aware of an invention in which a breakable portion of the air-line is carried in an exposed place outside the body of the car, which breakable portion is fractured by a track instrument on passing the same. I do not claim any method of car stopping by the fracture of the air-line carried in an exposed place, or by the actual fracture of the air-line in any part.

I claim:

In automatic train or car stopping apparatus, the combination with the brake pipe, of a valve having one side connected to said pipe and the opposite side opening into the atmosphere, a spring normally acting upon said valve to actuate the latter to open position to bleed the brake pipe, a projection on the casing of the valve, a pin in

terposed between said projection and the valve and acting to hold the latter in closed position against the action of said spring, a rod pivoted for swinging movement and having one end adapted to strike against said pin to release the valve and mutilate the pin so that the latter will be unfit for further service, and means on said projec-

tion to limit the movement of the valve to open position under the action of said 10 spring.

SARATH KUMAR GHOSH.
